UNITED STATES PATENT OFFICE.

JAMES G. LANGDON, OF WEST SOMERVILLE, MASSACHUSETTS.

SECTIONAL DESK.

Application filed October 11, 1921. Serial No. 506,947.

This invention relates to improvements in sectional desks.

The primary object of the invention is the provision of a desk, preferably for clerical purposes, including a machine supporting section, and a desk and stationery supply section.

A further object of the invention is the provision of a desk of the above described character including a plurality of sections and improved means for bracing, connecting and mounting the sections in stable manner, to provide a durable unit, capable of supporting stenographic, typewriting, adding and bookkeeping machines of considerable weight.

A further object of the invention is the provision of a desk, including detachable legs; a bracing member of novel formation being provided for mounting of the legs to said desk. A further object of the invention is the provision of a desk of the above described character and in which a plurality of sections are provided of such a nature as to be reversible with respect to each other.

Other objects and advantages will be apparent during the course of the following detailed description.

In the accompanying drawings forming a part of this specification, and wherein similar reference characters designate corresponding parts throughout the several views,

Figure 1 is a perspective view showing two of the desk sections assembled to provide a desk unit.

Figure 2 is a perspective view of the two sections shown in Figure 1 and assembled in different manner therefrom to provide a desk unit.

Figure 3 is a cross sectional view taken transversely through the desk sections and showing the manner of detachably assembling the same.

Figure 4 is a bottom plan view of the desk sections and showing the manner in which the parts of the same are assembled.

Figure 5 is a perspective view of a member used in detachably connecting the legs of the desk to the various sections thereof.

Figure 6 is a plan view of the leg connecting member, showing the same as made of sheet metal in its undeveloped form.

Figure 7 is an end view of a desk section and showing the manner in which the leg is assembled thereto.

In the drawings, wherein for the purpose of illustration is shown the preferred embodiment of my invention, the letter A designates the improved desk, including a section B for supporting a typewriting machine or the like, and adapted for detachable connection to a desk or stationary supply section C. A brace member D is provided of novel formation and adapted for detachably mounting the legs of the table A to the various sections thereof.

The improved table A simulates somewhat the sectional typewriter desk shown in the patent granted to me September 15, 1914, #1,110,948. It is the purpose of this invention to improve upon the desk shown in this patent, providing a more stable and durable connection for supporting the sections, to form a desk unit, as well as providing a better leg attaching arrangement. To this end, the machine supporting section B includes a bottom 10 and a top or supporting member 11 spaced therefrom as by intermediate spaced partitions 12. The side rails 14 and 15 are provided upon the right and left of the section B, respectively, and permanently attached to the bottom and top members 10 and 11 in any approved manner. The rear rail member 16 is provided for cooperation with the side rail members 14 and 15 in such manner that a marginal upwardly projecting rail enclosure is provided upon the sides and rear of the section B, and extending above the top surface of the member 11. Each of the permanently attached side rails 14 and 15 includes the lower relatively thick portion 17 and the upper reduced portion 18 to provide a shelf 19 for resting of the top member 11 thereupon; said portion 17 of the side rail members 14 and 15 being of the same height as the spacing partitions 12, and adapted to properly support the ends of the top member 11. The outside surfaces of the rail members 14 and 15 present a plain unbroken surface adapted for intimate contact in abutting a side of the desk section C, to be subsequently described. The partition members 12 are so arranged, as to the length of the desk section C, as to provide relatively wide end compartments 20 for receiving stationery supplies, such as paper and the like; and an intermediate relatively narrow compartment 21 is provided for receiving envelopes and the like. The compartments 20 and 21,

100
105
110

however, may receive any articles desired, consistent with the use to which the improved sectional desk A is put.

The section C may conveniently be called 5 the desk section, and is adapted for the taking of notes, writing of data, or the like. The same includes a top writing surface 25, having the skirt 26^a depending from said top 25 and offset inwardly from 10 the marginal edges of said top 25. A forward bottom member 26, and a rear bottom member 27, are provided for attachment to the lower marginal edges of the skirt 26^a and are provided with trackways 28 there- 15 upon and adjacent the sides 29 and 30 of the skirt 26^a, in order to support a drawer or other sliding member 31, substantially as illustrated in the drawings.

Each of the sections B and C are rectangular in formation, and in assemblage the major axis of the section B is disposed transversely or at right angles to the major axis of the section C. The section B is to be disposed rearwardly of the front of the section 25 C, substantially as illustrated in the drawings, and in such manner that the outer surface of one of the permanently attached rail members 14 or 15 abuts in intimate contact with the outside surface of one of 30 the longitudinal side members 29 or 30 of the skirt 26^a. It is preferred that the height of the section B, between the bottom surface of the member 10 and the very top of the marginal edges of the rail sections 14, 15 and 16, 35 be less than the height of the desk section C, as determined by the extreme bottom surface of the member 26 and the top 25, so that when the bottom surface of the member 10 lies flush with the bottom surface 40 of the member 26, the sections B and C will assume a position substantially as illustrated in Figure 3.

The section B is reversible with respect to the sides 29 and 30 of the desk section C; 45 the rail members 14 and 15 being provided for respective abutment against the sides 29 and 30, when to the left and right respectively of the desk section C. In order to provide a stable and durable connection between 50 the sections B and C, and one which is capable of supporting the excessive weight placed upon the machine supporting section B, a pair of angle brace members 35 and 36 have been provided for attachment 55 to the bottoms 10 and 26 of the sections B and C. Each of the angle braces or connecting bars 35 and 36 are provided with a pair of securing elements 37, such as screws, bolts or the like, adapted for engagement 60 upwardly through the bottom 10 of the section B. Likewise, each of the members 35 and 36 are provided with a pair of securing elements 38 adapted for engagement upwardly through the bottom member 26 of the 65 section C. The brace bars 35 and 36 are pro-

vided for disposition adjacent the forward and rear edges of the machine section B, and thus providing a well balanced supporting structure by holding the outer surface of a side rail of section B in abutting relation with a side of the skirt 26^a. 70

When the sections B and C are connected to form a desk unit, a pair of legs 40 and 41 are provided upon the ends of the section C; a single leg being provided upon the end 75 of the section B remote from the connecting bars 35 and 36. The leg 40 is, of course, attached to the bottom member 27 of the section C substantially as illustrated in Figure 80 4; the member 41 being attached to the bottom surface of the member 26, and adjacent the rear connecting bar 36. Thus, three legs are provided for a desk unit A when the sections B and C are assembled, as above 85 described, said legs 40, 41 and 42 being properly connected to the bottom surfaces of the units B and C by the brace members D to be subsequently described.

The brace member D for attachment of the legs to the desk unit A is of novel formation, 90 including the triangularly shaped bracing pieces 45 and 46, of like formation, and connected in diverging relation by a flat vertical attaching section 47 of rectangular appearance. The upper marginal edges of the reinforcing wings 45 and 46 are provided with horizontal attaching flanges 48 and 49 respectively, and inturned toward each other, the attaching upper surfaces of the flanges 48 and 49 lying in the same plane for attachment 95 to the bottom of the sections B and C. The edges 50 of each of the flanges 48 and 49 are bevelled, as illustrated in Figures 5 and 6 of the drawings in order to provide 100 for the even formation and bending of the bracket or brace D. It can readily be seen that the vertical attaching portion 47 of the member D is at right angles to the horizontal attaching flanges 48 and 49, and firmly and securely connected by the diverging 105 wing portions 45 and 46. Suitable apertures 51 are provided in the flanges 48 and 49 for attachment to the bottom of the sections B and C. Similarly, suitable apertures 52 are provided in the vertical attaching flange 47 for receiving certain bolts 110 or other members to be subsequently described, for securing of the member D to the legs of the improved typewriter desk A. 115

As illustrated in Figure 4 of the drawings, the legs 40 and 41 are attached to the bottom members 27 and 26 respectively of the section C by the brace members D. The flanges 48 and 49 of these brace members D receive suitable attaching rivets or elements 53, for securely mounting the legs 40 and 41, said legs receiving suitable detachable bolts 54 adapted for engagement in the apertures 52 of the vertical attaching portion 47 of brace members D. It is preferred, 120

- that the attaching portion 47 of each of the braces D face to the outside of the end of the section upon which the same is placed, in order to prevent spreading of the desk legs. The leg 42 of the section B is assembled to the bottom 10 by a brace member D. The flanges 48 and 49 of this brace member D receive detachable screw or bolt elements 56, adapted for engagement in suitable apertures 58 tapped upwardly in each end of the bottom 10, and whereby the brace member D may be reversed for placing the leg 42 adjacent either of the side rails 14 and 15, said leg 42 of course, always being positioned remote from the side rail which abuts against the skirt 26^a. Detachable bolt elements 58^a are provided for engagement of the leg 42 to the vertical attaching portion 47.
- As is illustrated throughout the drawings, the section B can be reversed to the left or to the right of the desk section C. Consequently, the supporting bars 35 and 36 are removable, suitable apertures 59 having been provided upon the bottom 26 adjacent both sides of the section C and apertures 60 have been tapped in each end of the bottom 10, for receiving the elements 37 and 38, to selectively mount the bars 35 and 36. As is illustrated in Figure 4, the section B is on the left side of the section C and the positions of the various legs have been illustrated in full lines thereon. Should it now be desired to position the unit B upon the right side of the section C, the leg 42 will necessarily have to be detached and swung into the position illustrated in dot and dash lines in Figure 4. Similarly, the bars 35 and 36 will have to be detached from the bottom member 26, and swung into position that the same may be attached by means of the securing members 37 and 38 to the apertures 59 and 60 which are shown in full lines in Figure 4.
- From the foregoing, it can be seen that a structure has been provided including a machine supporting section and a desk section, which are detachable and reversible with respect to each other to provide a unit of considerable flexibility. The retaining or connecting angles 35 and 36 securely support the sections B and C against liability of sag; and due to the broad area defined by the outside surfaces of the rail members 14 and 15, the joint or connection of the sections is additionally reinforced. The units A may be connected in rows, with the sections B upon each side of a section C, as is clearly brought out in my Patent #1,110,948.
- Various changes in the shape, size and arrangement of parts, may be made to the form of the invention herein shown and described, without departing from the spirit of the invention or the scope of the claim.
- I claim:
- In a desk, a machine supporting section including a top member, a bottom member, end rails securing the top member and bottom member in spaced relation so that said rails are each disposed above and below the plane of the top member and have outside plane surfaces of the same dimensions and free of projections, a leg for detachable connection to the bottom member of said section adjacent either end rail, a second section including skirts at opposite sides thereof against which the plane outer surface of either end rail of said first mentioned section may abut, means for coupling the sections in such relation, and leg supporting means for the second section.

JAMES G. LANGDON.
